UNITED STATES PATENT OFFICE

2,059,706

AIR PAINTING DEVICE

Jens A. Paasche, Wilmette, Ill.

Application July 16, 1931, Serial No. 551,137

11 Claims. (Cl. 299—140)

The invention relates generally to air painting devices and more particularly has reference to painting devices in which the application of paint, color coats, or the like, is produced by air under pressure.

An object of the invention is to provide a device of this nature which embodies new and improved means for actuating the device.

Another object of the invention resides in the provision of such a device in which the pressure of the air supplied to the device is utilized in a novel manner to actuate the means by which the device is controlled.

More particularly stated, an object of the invention resides in the provision of an air painting device for applying paint or other surface-coating material by means of air under pressure, which device embodies a hollow barrel having valve means therein for controlling the passage of paint and air therethrough, and means in said barrel arranged to be actuated by incoming air to open said valve means, said parts being so related that the air after actuating said valve means passes through said barrel to produce a flow of the coating-material from the device.

In conjunction with the foregoing objects, the invention has as an object the provision of a novel device which is adapted to be used in banks or batteries of several devices, all of which may be under the control of a single instrumentality.

Other objects and advantages will become apparent in the following description and from the accompanying drawing, in which:

Figure 1 is a view partially in plan and partially in elevation illustrating an apparatus embodying the features of the invention.

Fig. 2 is a longitudinal, axial section on an enlarged scale through the air painting device.

Figs. 3 and 4 are views partially in section of different types of spray nozzles and their associated control elements utilized as replacement assemblies for the device shown in Fig. 2.

Fig. 5 illustrates an extension and a modified form of spray nozzle for use in connection with the device illustrated in Fig. 2.

Fig. 6 is a view on a reduced scale of a modified form of apparatus.

In describing the preferred embodiment of the invention, it will be considered that the device is adapted for atomizing paint or other coating material by air under pressure. It should be understood, however, that the device is capable of atomizing liquids, other than paint, by pres-

sure fluids, other than air, and the terms "paint" and "air" are herein employed, not in a limiting sense, but for the purpose of simplifying the discussion of the invention. Moreover, while the invention is susceptible of various modifications and alternative constructions, I have shown in the drawings and will herein describe in detail the preferred embodiment, but it is to be understood that I do not thereby intend to limit the invention to the specific form disclosed, but intend to cover all modifications and alternative constructions falling within the spirit and scope of the invention as expressed in the appended claims.

In the embodiment of invention which has been selected for the purpose of illustration, and with particular reference to Fig. 2, the body of the spraying device comprises a barrel 10 in the form of a tubular member which is preferably cylindrical and has a portion 11 of restricted size at one end thereof. The outer end of the restricted portion 11 has an annular flange 11a thereon providing an abutment for an inturned shoulder on a gland 12 to hold the gland rotatably on the portion 11. The gland is internally screw threaded to engage complementary screw threads on a head 13 having an internal passageway 14 at the front end thereof. Paint or other material to be sprayed is supplied to the passageway 14 through an integrally formed nipple 15. The union between the head 13 and barrel portion 11 allows the head to be rotatably adjusted about its axis so that the paint may be supplied to the device from any angle through the nipple 15. The head is provided with a longitudinal passageway 16 for air, which passageway substantially divides the head into two concentrically arranged parts which are maintained in position by the integral formation of the head and nipple 15.

The front end of the head receives a nozzle assembly, generally designated at 17, arranged to be detachably secured thereto. The nozzle assembly comprises a centrally disposed tapering tip 18 having a tapering axial bore 19 communicating with the paint passageway 14 and an annular passageway 20, registering with the air passageway 16. The tip is held in assembled but detachable relationship on the head by such means as a nut 21 engaging the tip and having external screw-threaded engagement with the front end of the head.

The air passageway 20 in the tip stops short of the passageway 19 for paint and an air cap 22, which is detachably secured in concentric rela-

tionship to the tip by such means as a gland 23 carried by the nut 21, cooperates with the tip in providing an annular restricted emission port 24 about the restricted mouth 25 of the bore 19. 5 The flow of air under pressure through the port 24 is effective in a manner which is well-understood to create and eject a spray of paint from the device.

Within the bore 19 a valve seat is provided 10 which cooperates with a valve 26, herein shown as a needle valve, for controlling the flow of paint from the device. The valve 26 is actuated by means of an integrally formed valve stem 27 which extends rearwardly and axially through 15 the head 13 and into the larger portion of the barrel 10. The head 13 is provided with a rearwardly facing axial bore 28 to receive packing 29 of any suitable character. Preferably, the packing is held in place by means which may be removed from the device as a unit in order to 20 permit replacement thereof by a corresponding unit of different size. To this end, the rear face of the head 13 flares outwardly, as at 30, from the bore 28 to cooperate with a complementary surface formed on the end of a packing and bearing member 31. This member has an annular shoulder 32 thereon arranged to abut an outwardly 25 facing shoulder 33 provided on the end of the restricted portion 11 of the barrel. Thus, when 30 the head 13 is screwed into the restricted portion 11, the bearing member will be securely clamped between the shoulder 33 and the end of the head.

The front end of the bearing member is radially bored, as at 34, to form when the parts are 35 assembled a continuation of the bore 28. Hence, the bore 34 may, and usually does, receive a portion of the packing material 29. The rear portion of the bearing member is apertured to permit the stem 27 to extend therethrough. Surrounding the stem 27 within the bore 34 is a 40 conventional packing follower 35 which is urged into compressing engagement with the packing material 29 by such means as a helical spring 36 encircling the stem 27 and bearing between the 45 packing follower 35 and the base of the bore 34.

The larger portion of the barrel 10, which is disposed rearwardly of the restricted portion 11, defines a cylinder compartment 37 having a rearwardly directed open face arranged to be closed 50 by an end cap 38 detachably screw-threaded onto the barrel. Within the chamber 37 is located means for operating the needle valve 26, which means is responsive to the pressure of the air as the air is delivered to the nozzle. Thus, the end 55 of the valve stem 27, which extends into the chamber 37, passes through a piston assembly, generally designated 39, arranged for reciprocating movement within the chamber. The piston assembly comprises a central, elongated hub 40 which preferably has a packing assembly mounted 60 in a bore 40a therein and similar generally to that located forwardly thereof in the bores 28 and 34. The hub 40 has an integrally formed annular flange 41 thereof arranged to cooperate 65 with a disk 42, having screw-threaded engagement with the hub 40, to secure a flexible piston washer 43 of leather or the like to the hub. Air under pressure is introduced at some point intermediate the piston assembly and the nozzle and 70 it is preferred that the barrel 10 be apertured, as at 44, near the front end of the chamber 37 to provide an air inlet port which is defined by the customary nipple 45. The piston assembly 39 is spaced from the front end of the chamber 37 a 75 distance sufficient to clear the port 44.

It will be apparent from the foregoing that the introduction of air through the aperture 44 will cause the piston to move rearwardly. The valve stem 27 beyond the piston assembly carries a piston engageable head 49 spaced a short distance 5 therefrom to provide for a limited amount of lost motion before the piston contacts the head to move it rearwardly and thereby open the needle valve 26. Return movement of the piston is effected, in the present instance, by suitable resilient means bearing between the end cap 38 and the piston assembly 39. Thus, opposed bosses 46 and 47, on the disk 42 and end cap 38 respectively, provide seats for a helical spring 48 arranged to exert a force for normally holding the 10 valve 26 seated. The boss 46 incidentally is the part of the piston assembly which engages the head 49. The rear face of the head 49 is cup-shaped to receive one end of a second and smaller helical spring 50, the other end of which is centered about a pin 51 carried by a tension adjusting screw 52 mounted in the end cap 38. Thus the force exerted on the valve 26 may be adjusted 15 as required.

In order positively to insure operation of the 25 piston whenever air under pressure is admitted to the inlet aperture 44, an air control valve is interposed between the aperture 44 and the nozzle. This air control valve preferably is actuated by the piston mechanism 39 to open prior 30 to the opening of the needle valve 26. In the present embodiment, the forward end of the piston hub 40 is tapered, as at 53, to form a valve member. The barrel 10 is provided with an internal annular flange 54 defining a central aperture and finished to provide a valve seat for the 35 valve member 53.

When the parts are assembled, the arrangement is such that the valves 26 and 53 open and close according to the movements of the 40 piston assembly 39. The valve 53 controls the flow of fluid from the air inlet aperture 44 to the nozzle member and, when the device is inoperative, prevents the flow of air to the nozzle. It will be evident, therefore, that, when air under 45 pressure is first admitted to the device, the piston assembly 39 will be positively moved rearwardly of the barrel to first open the air valve 53 and permit a flow of atomizing air to the nozzle. Subsequently the boss 46 engages the head 49 50 on the valve stem and opens the needle valve 26 gradually allowing paint to flow through the nozzle into the air stream. The piston will be held in its rearward position as long as air is admitted to the barrel, but as soon as pressure 55 on the piston is relieved, the springs 48 and 50 operate individually to close both the air controlling and paint controlling valves.

While the present device may be used by itself, it is as readily capable of being employed in 60 banks or batteries of two or more devices which are controlled and actuated by a single instrumentality. The use of several devices is desirable when the devices are employed in connection with an automatic paint applying machine 65 such, for example, as that illustrated and described in my copending application Serial No. 523,393 filed March 18, 1931.

One preferred form of means for actuating one or more of the paint applying devices is shown 70 in Fig. 1. Air under pressure is supplied to the device in the following manner: A conduit 55 is connected through a swivel connection 56 with the air inlet nipple 45. The conduit 55 is preferably in the form of a rigid pipe or tube which 75

is engaged by a universal bracket 57 for supporting the device from a stationary part 58. A flexible conduit 59 provides communication between the rigid conduit 58 and a valve mechanism, generally indicated at 60, from which a conduit 61 leads to a source of air under pressure (not shown). The valve mechanism 60 includes a reciprocable valve member 62 which is normally held in valve-closing position by a spring 63. A valve stem 64, connected with the valve 62, extends outside the valve housing and is engageable by a pivoted valve-actuating cam 65 mounted externally of the valve mechanism. By this arrangement, the means by which the device is manipulated may be mounted at a considerable distance from the device itself as, for example, adjacent the edge of a table or moving conveyer on which articles to be painted are mounted. Such means as a spindle 66, carried by the table and having a cam follower 67 thereon arranged in the movement of the table to engage the cam 65, may be employed to actuate the valve at predetermined points in the movement of the table. Preferably, a cut-off valve 68 is interposed between the valve mechanism 60 and the device for preventing actuation of the device as desired.

When several of the devices are employed as a battery, all of such devices may be actuated by the single valve mechanism 60. In such a case, a branch conduit 69 establishes communication between the conduit 59 and the several additional devices. As a result, when the valve mechanism 60 is actuated, air under pressure is delivered to the barrel of each device to actuate the devices simultaneously. Obviously, if each device is provided with a cut-off valve 68, they may be selectively used. A conduit 70 supplies paint from a suitable source (not shown) to the nipple 15.

Fig. 6 shows a modified form of the structure shown in Figs. 1 and 2 wherein the atomization may be accomplished by air under less pressure than that which actuates the piston assembly. This end is attained by providing a pressure reduction valve between the supply line and the nozzle. One form of means as shown in Fig. 6 comprises a short conduit 16^a extending from the nipple 45 adjacent the swivel connection 56 and communicating with the passageway 16 preferably on the side of the head 13 opposite the paint inlet nipple 15. This conduit 16^a is controlled by a manually operable needle valve 16^b of customary construction for regulating the air flow to the nozzle. In this construction the passageway 16 between the inlet mouth of the conduit 16^a and the piston assembly is closed. Thus, the device is adapted to be operated by air under low pressure while the piston is actuated by full pressure and thereby provides a simple, economical and positively operating structure.

Inasmuch as the present device is particularly adaptable for use in connection with paint applying machines which generally are capable of handling many different types of objects, the invention provides means by which the device may be readily adjusted or converted to adapt it to properly coat these different types of objects. Thus, the nozzle assembly is readily detachable from the head 13 to allow the characteristics of the coating spray created by the device to be varied to provide a finer or a coarser spray. This particular adjustment, of course, has its limits and, where the nature of the spray desired is beyond these limits, a replaceable assembly such as that shown in Figs. 3 or 4 is provided.

The assembly shown in Fig. 3 embodies a nozzle and head assembly, similar in general structure to that illustrated in Fig. 2, but arranged to produce a spray which may be either finer or coarser than that which the assembly shown in Fig. 2 is capable of delivering. Inasmuch as the passageway for the material through the nozzle of the assembly illustrated in Fig. 3 will probably be of different dimensions, a valve 26 of proper size and its integrally formed valve 27 is supplied as a part of the assembly. Packing material 28 for the valve stem 27 is likewise provided.

The device may be readily converted by means of these different assemblies in the following manner. The head 13 is first unscrewed from the restricted portion 11 of the barrel, the end cap 38 is removed from the barrel, and the valve stem 27 withdrawn through the open end of the barrel. A head 13 having a desired type of nozzle thereon, and the new packing material therein, is then screwed onto the barrel. The supplanting valve stem is assembled with the piston and the parts inserted in the barrel. The valves 26 and 53 are properly adjusted, the end cap 38 replaced on the barrel, and the device is ready for operation.

The assembly shown in Fig. 4 is adapted to produce a very heavy or coarse spray and embodies a nozzle suitable for this purpose. In this assembly, it may be desirable to provide a complete bearing member assembly 31 as well as a different piston assembly. This is in order that a proper cooperation between these parts and the supplanting valve stem 27 may be obtained. Otherwise, the manner of assembling the parts with the barrel is the same as has been described.

In Fig. 5 means is shown for increasing the distance between the barrel and the nozzle. This means comprises a tubular extension 71 having a gland 72 at one end arranged to engage the screw threads formed on the forward end of the head 13. The other end of the extension is screw threaded to receive a suitable nozzle assembly 13. The extension is advantageous since the device, when used in connection with a paint applying machine, is ordinarily mounted on a stationary part and its adjustment relative thereto is limited. Consequently, where it is desirable to deliver the spray at some point which is beyond the ordinary limit of adjustment, the extension 71 is employed. Obviously, this extension may be curved if desired while needles 27 of corresponding length are used to shut off material at the end of the extension.

It will be apparent from the foregoing that a novel device has been provided which is very simple in construction. The device is efficient in operation, and is readily adapted for multiple use in batteries which may be simultaneously operated. Furthermore, the device may be converted by merely replacing certain parts with corresponding parts so that the device may meet all operating conditions and requirements.

I claim as my invention:

1. In a spraying device, the combination of means for creating and ejecting a spray of coating material therefrom by pressure fluid, means for controlling the flow of coating material thereto, means for controlling the flow of pressure fluid through said device, an operator movable in response to the force of said pressure fluid, means connecting said operator with said pressure fluid control means, a lost motion connection between said operator and said coating material control means whereby actuation of the

operator effects successive movements of said control means, and resilient means for said pressure fluid control means and said coating material control means acting separately to oppose movement thereof out of a normally closed position.

2. A spraying device comprising, in combination, a barrel having an emission nozzle thereon and including an axially disposed material passageway and an air passageway located eccentrically of the axis, an axial needle valve controlling the material passageway at the nozzle, an air valve concentric with said needle valve and controlling a flow of air to the air passageway, an air operated piston in said barrel rigid with said air valve and movable when subjected to air pressure to open said air valve, said needle valve including a shank adapted to pass axially through and slide relative to said piston, a head on said shank engageable by said piston to open the needle valve after the air valve has been opened, springs engaging said piston and said shank to separately hold the valves associated therewith normally closed, and an air inlet to said barrel in operating communication with said piston.

3. A spraying device comprising, in combination, a barrel having an emission nozzle thereon and including an axially disposed material passageway and an air passageway located eccentrically of the axis, a needle valve controlling the material passageway at the nozzle, an air valve controlling a flow of air to the air passageway, an air operated piston in said barrel rigid with said air valve and movable when subjected to air pressure to open said air valve, said needle valve including a shank adapted to pass through and slide relative to said piston, a head on said shank engageable by said piston to open the needle valve after the air valve has been opened, and an air inlet to said barrel in operating communication with said piston.

4. A spraying device comprising, in combination, a barrel having an emission nozzle, an air operated piston therein spaced from said nozzle, an axial material passageway communicating with said nozzle, a needle valve in said nozzle controlling the emission of material therefrom, said nozzle having a shank bearing in said piston and slidable relative thereto, a lost motion connection between said shank and said piston for actuating said needle valve, a passageway for air to said nozzle, an air valve in said passageway connected with said piston for movement therewith, and a passageway for delivering air under pressure to said piston and air passageway.

5. A spraying device comprising, in combination, a barrel formed of transversely divided front and rear sections, said front section having a nozzle thereon and a material passageway therein communicating with said nozzle, a piston in said rear section, communicating air passageways in said front and rear sections, a needle valve for controlling a flow of material through said nozzle and having a part extending into said rear section and operatively connected with said piston, an air valve actuated by said piston, and a removable packing gland about said needle valve part including means adapted to be clamped between the front and rear sections when the device is assembled.

6. A spraying device comprising, in combination, a barrel having a nozzle thereon, means for supplying air under pressure and material to be sprayed to said barrel, a valve controlling

the flow of material through said nozzle, a valve for controlling the flow of air pressure to said nozzle, an operator for the valve controlling the flow of material to the nozzle including a stem, actuating means mounted for slidable movement relative to said stem under the influence of the pressure of incoming air and having an operating connection with said air controlling valve, means on said stem disposed for abutment by said actuating means in the relative sliding movement thereof, and resilient means bearing individually on said actuating means and on said stem for returning each separately to the idle positions thereof.

7. In a spraying device, the combination of means for creating and ejecting a spray of coating material therefrom by fluid pressure, means for controlling the flow of coating material thereto, means for controlling the flow of pressure fluid through the spray means, an operator movable in response to the force of said pressure fluid, a rigid connection between said operator and said pressure fluid control means, a lost motion connection between said operator and said coating material controlling means, whereby actuation of the operator effects successive movements of said control means, and resilient means for said pressure fluid control means and said coating material control means acting separately to oppose movement thereof out of a normally closed position.

8. A spray gun comprising a body with a material passageway therethrough terminating at its front end in a discharge nozzle, a cylinder separate from said passageway, a piston in said cylinder, a needle extending through said piston with its front end in cooperative relation to said nozzle, means to admit fluid pressure to the front end of the cylinder to move said piston rearwardly, a spring in said cylinder opposing the rearward movement of the piston, a head on the needle valve engageable by said piston in its rearward movement to open said needle valve, and a second spring acting on the needle valve independently of the piston to oppose the opening of said needle valve.

9. A spraying device comprising, in combination, a barrel having a nozzle thereon, controllable means for supplying air under pressure and material to be sprayed to said barrel, a valve controlling the flow of material through said nozzle and a valve operator for said valve including a stem, actuating means mounted for slidable movement relative to said stem under the influence of the pressure of incoming air, means on said stem disposed for abutment by said actuating means in the relative sliding movement thereof to move said stem longitudinally for opening said valve, and resilient means bearing individually on said actuating means and on said stem for returning each separately to the original or closed position thereof.

10. A spray gun comprising a body with a material discharge passageway therethrough, a needle valve cooperating with the discharge end of said material discharge passageway, a spring tending to hold said valve closed, a cylinder separate from said passageway, a reciprocable piston, a second spring acting on the piston to move it in one direction, said piston being movable by compressed air admitted to the cylinder in opposition to the spring, said piston having a motivating engagement with the needle valve when moving in one direction and being movable in-

dependently of the needle valve in the opposite direction.

11. In a pneumatically operable spraying device of the character described, the combination of a spray nozzle, material-delivery means communicating with said nozzle, a valve having pressure fluid responsive actuating means for controlling the delivery of material to said nozzle, a conduit for delivering pressure fluid to said ac-

tuating means, a duct leading from a point adjacent to said actuating means for conveying pressure fluid to said nozzle to effect a spray of material therefrom, and a valve in said duct manually adjustable from a location exteriorly of the device to control the flow of pressure fluid to the nozzle.

JENS A. PAASCHE.
